MAGAZINE TYPE HOT-AIR FURNACE

William E. Strange, Brandon, Manitoba, Canada

Application April 28, 1950, Serial No. 158,688
In Canada March 6, 1948

1 Claim. (Cl. 126—107)

1

The invention is particularly designed for domestic heating and the principal objects thereof are to provide a hopper which will feed coal into the firebox by gravity and to provide an unobstructed entrance on the other side of the firebox for the removal of clinkers or ashes.

A further object of the invention is to provide a relatively narrow grate completely across the firebox for a reduced burning area, formed to carry a maximum amount of fuel, and such that the coal will be fed onto the fire at a sloping angle.

A further object of the invention is to design the firebox of a relatively narrow cross section while presenting a relatively large combustion chamber for maximum heat distribution.

A further object of the invention is to provide a closed chamber on either side of the firebox for heat transfer therefrom to the hot air chamber, and by doing so, eliminate the use of firebrick and the like on the walls of the firebox.

A still further object of the invention is to provide a radiator within the air chamber of the furnace for further heat value from the products of combustion.

With the above important and other minor objects in view, which will become more apparent as the description proceeds, the invention consists essentially in the design, construction and assembly of the various parts hereinafter more particularly described, reference being had to the accompanying drawings in which:

Figure 1 is a vertical sectional view through my new furnace.

Figure 2 is a horizontal sectional view taken on the line 2—2, Figure 1 and showing the hopper in dotted outline.

Figure 3 is a vertical sectional view taken on the line 3—3, Figure 1 and showing the hopper position in dotted outline.

Figure 4 is a horizontal section taken on the line 4—4, Figure 1.

Figure 5 is a perspective view of the grate.

In the drawings like characters of reference indicate corresponding parts in the several figures.

The body of the heater comprises an inverted cup-shaped cast cylinder 1 (see Figure 3). The lower open end of this cylinder is received by a circular cast base member 2, supported on the floor. The base member is provided with an encircling flange 3 which receives and retains the cylinder while the lower part of the circular portion is rounded, as indicated at 4.

A pair of spaced vertical heavy plates 5 and 6 are positioned across the central lower interior part of the cylinder 1 while a rectangular-shaped opening 7 is cut in the wall of the cylinder 1, opposite the ends of the heavy plates 5 and 6 and to a width approximately the same as the space between these plates. This opening forms an entrance to the space between the plates. A rectangular-shaped open-ended box 8 is formed from sheet metal and welded to the cylinder 1 and the base member 2 at the opening 7. The lower side of this box forms a continuation of the upper part of the base member, the sides form a continuation of the plates 5 and 6, while the upper portion forms the roof, and together with the sides and bottom, present a sealed passageway into the cylinder. The space between the plates 5 and 6 is utilized for the firebox and the ash chamber as will be later described.

The upper edges of the plates 5 and 6, within the cylinder 1, turn over at an angle to present a pair of sloping surfaces 9 and 10 which pass outwardly to the cylinder walls and are welded thereto to create a pair of closed semi-circular chambers 11 and 12 on either side of the heavy plates 5 and 6. From the above description it will be seen that, when the products of combustion rise between and above the plates 5 and 6, they will be able to expand the full area of the cylinder 1, above the plates 9 and 10. This area, indicated by the number 13, I term the combustion chamber.

On each of the interior sides of the heavy plates 5 and 6, a pair of guides 14 and 15 are provided. These guides are formed integral with the plates, the guides 14 being at a slight slope at one side of the centre of the cylinder 1 while the guides 15 are positioned at an acute angle and extend to the opposite ends of the plates 5 and 6. These guides form a saddle for the reception and support of a grate 16, best shown in Figure 5. This grate is formed in one piece, of an angular shape, and is provided with a plurality of relatively vertical and horizontal slots 17, separated by a cross portion 18. These slots provide upward passages for air therethrough and downward passages for ash in the burning of the fuel.

A fixed sloping plate 19 is provided within the box 8 and is aligned with the bottom of the grate but separated therefrom to provide an opening 20 therebetween. A panel 21 covers this opening, slides on the plate 19, and is supported by bars 22, when the panel is over the opening. The bars 22 have one end supported by the sides

2

sides of the plates 5 and 6. A catch 23 is provided on the panel for hooking the end of a poker therein so that it can be bodily end shifted back and forth over the opening.

A hot air casing 24 encircles the cylinder 1 and the upper end is closed by an inverted cone-shaped portion 25 so that hot air rising therein will be deflected to the upper corners and pass out the hot air pipes, indicated at 26. This casing is circular but slightly off-set from the centre of the cylinder 1 so as to enclose the box 8.

A hopper 21, of a rectangular funnel-shape, is mounted outside of the casing 24 but adjacent the cylinder 1. The upper end of this hopper is approximately the height of the cylinder and is provided with a suitable removable cover 28 which can be manually lifted by a handle 29 to expose the interior. The lower part of the hopper tapers sharply toward the casing 24 and terminates in a sloping pipe 30 which passes through holes in both the casing 24 and the cylinder 1 to be received at its lower open end between the plates 5 and 6 above the grate. From the above it will be apparent that when the cover 28 is removed and coal is poured into the hopper, it will pass down through the pipe 30 and will feed by gravity onto the grate 16 until the grate is covered and the upper edge of the coal, within the cylinder 1, will be approximately at the angle indicated by the dotted line 31.

A flat vertical cast front 32 is provided on the front of the furnace. The protruding edges of the box 8 bolt to this front while the casing 24 fastens to the edges thereof. A pair of upper and lower doors 33 and 34 are provided on the front for entrance to the upper part of the grate and the ash pit respectively. When the upper door 33 is opened, a complete visual observation can be made of the fire resting on the grate while a poker can be inserted, through the opening, to stir the fire and draw out any clinkers. The same poker can be hooked into the catch 23 to draw the panel 21 back and expose the opening 20. When so exposed, the poker can then be used to draw the clinkers and ashes off the grate to fall through the opening into the ash pit. These ashes and clinkers fall into a suitable box 35 supported by the base member 2 and, when filled, this box can be withdrawn through the opening normally closed by the door 34.

A curved radiator 36 is mounted within the casing 24 and passes partly around the cylinder 1 above the box 8. This radiator is rectangular in cross section and the upper end is provided with a pipe 37, suitably bolted to and in communication with the upper end of the combustion chamber 13. The lower portion of the radiator is provided with an outlet pipe 38 which passes through the casing 24 and connects to a suitable smoke pipe (not shown). A water reservoir is indicated at 39.

In operation, the fire is started in the lower corner of the grate 16 in any suitable manner and the ash pit door 34 is opened slightly to supply the necessary draft. If desired, an air register or regulator may be provided in this door for better control of the air entrance. The air passes from the ash pit, through the grate, and supplies oxygen to the burning fuel. The products of combustion pass up and spread out in the combustion chamber 13, thence into the radiator 36, and out the pipe 38. The walls of the combustion chamber and the walls of the radiator both supply heat to the air in the hot air casing 24. This latter air rises and passes out the hot air pipes

26 while a fresh supply of cool air comes in through the cold air pipes, indicated at 40.

In this connection it might be mentioned that the fire on the grate transmits heat to the heavy plates 5 and 6, which in turn heat the air in the closed chambers 11 and 12 by contact. The air in the closed chambers circulates and carries the heat to the lower walls of the cylinder 1, or at least to that part which forms the walls of the chambers. This transferred heat is then delivered to the cool air passing thereover and coming in from the cold air pipes 40. This method of heat transference, cools and relieves the heavy plates 5 and 6 from the intense temperature created by the fire, separates the plates from the direct draft of cool air coming from the cold air pipes and so prevents distortion of the plates 5 and 6, while the lower part of the cylinder, being circular, forms a larger area for improved transfer of the heat to the incoming and rising air in the casing 24.

In ordinary furnaces, having a circular firepot, the circular construction greatly reinforces the walls. However, in all such furnaces, firebrick is used on the inside of the firepot to protect these walls from the excessive heat of the fire. If this firebrick were not used the walls would become extremely hot and the cold air from the cold air pipes, coming into contact with these hot surfaces, would buckle or break them. In this furnace, the heavy plates 5 and 6 are flat and therefore not as strong as circular ones. Yet, no firebrick is used because, although they become extremely hot, the chambers 11 and 12 form a cushion between the heated surfaces of the plates and the cool air in the casing 24 and so take the place of firebrick. The air in these chambers becomes heated to a high temperature but is continually circulating to deliver the heat to the walls of the container 1, which is relatively thin and of larger area and so dissipates the heat rapidly into the air in the casing. Accordingly, broken or crumbling firebrick creates no problem in this furnace and the chambers form a permanent protection for the plates 5 and 6. In tests on this furnace, the chambers 11 and 12 were filled with sand. It was found that when these chambers were so filled, the heat of the fire buckled and ruined the heavy plates 5 and 6. However, when the chambers 50 were left empty, the circulation of air in the chambers, above described, dissipated the heat very quickly and completely eliminated such buckling.

Due to the shape of the grate, the burned-out ash and clinkers have a tendency of sinking to the lowest portion thereof so that they naturally collect at one place. By having the door 33 on the opposite side of the furnace to the hopper, the operator can open same and have full observation of the condition of the fire. The same opening permits the use of a poker into the fire to catch and roll out any formed clinkers at the bottom, and when same are brought to the surface, it is a simple matter to pass them down through the opening 20 into the ash pit. The walls of the combustion chamber present a large outer surface for air contact, and together with the radiator and heat from the closed chambers, result in a very efficient heat delivery from the furnace. Due to the fact that the grate is fixed, and therefore never riddled or shaken or agitated, the furnace presents an ideal medium for the burning of soft, cheap lignite fuels which normally pulverize under heat. In ordinary furnaces such pulverized fuel falls in red hot ashes

into the ash pit when the grates are riddled and the heat value is lost. While this furnace is adapted for burning this type of coal it can also burn other types providing they are of a size small enough to roll down the coal bed as explained. By forming the heater part of the furnace in a cylinder and partitioning off the lower parts to create the closed chambers, a narrow sloping area is provided for the firebox between the chambers for clear visual observation of the fire, a large combustion chamber is formed thereabove for maximum heat distribution, while maximum strength still results from the cylindrical construction.

While I have shown and described the invention as a hot air furnace it will be readily understood that the same could be used in the form of a stove. When so used, the radiator would be dispensed with and a direct connection made to the chimney from the combustion chamber.

What I claim as my invention is:

A furnace comprising, a vertical cylinder closed at its top serving as a fire box and heat exchange structure having a flue extending from the upper part thereof, a pair of spaced apart vertical heavy plates positioned across the lower interior portion of said cylinder spaced apart to provide a fire box of substantially rectangular shape and each turned over at an angle at the upper edge presenting upwardly and outwardly sloping walls connected with the wall of the cylinder to thus close off substantially semicircular chambers on the outer sides of the heavy plates

and consequently the fire box, a hot air casing encircling and spaced from the cylinder to provide air circulation around and above said cylinder, an angular shaped lattice grate mounted substantially rigidly between and supported by said vertical plates in the lower part of the cylinder and the fire box and inclined at an angle so said grate forms a pocket for the support and burning of fuel therein, doors and openings 10 through said casing and cylinder giving access to said fire box above and below the grate, a fuel feed hopper exteriorly of the casing having a chute discharging fuel by gravity at the rear upper end of said grate, heated air outlet pipes 15 from the upper part of the casing, and cold air supply pipes leading into the casing and supplying air in the area of the wall of the cylinder having the closed off semicircular chambers.

WILLIAM E. STRANGE.
